UNITED STATES PATENT OFFICE.

SOLOMON S. FRANCIS, OF OAKESDALE, WASHINGTON.

DESIGN FOR A STEAM-JET OVEN-CLEANER.

52,699.

Specification for Design.

Patented Nov. 19, 1918.

Application filed July 2, 1918. Serial No. 243,074. Term of patent 14 years.

To all whom it may concern:

Be it known that I, SOLOMON S. FRANCIS, a citizen of the United States, residing at Oakesdale, in the county of Whitman and State of Washington, have invented a new, original, and ornamental Design for a Steam-Jet Oven-Cleaner, of which the following is a specification, reference being had to the accompanying drawing, forming a part thereof.

The figure is a perspective view of the steam jet oven cleaner, showing my new design.

I claim:—

The ornamental design for a steam jet oven cleaner, substantially as shown.

SOLOMON S. FRANCIS.

Witnesses:

GEO. W. HARRIS,
P. L. CRAWFORD.
